CLAIM

We claim the ornamental design for a nasal spray device, as shown and described.

DESCRIPTION

FIG. 1 is a top perspective view of a nasal spray device incorporating our design.

FIG. 2 is a right side view thereof.

FIG. 3 is a front view thereof.

FIG. 4 is a left side view thereof.

FIG. 5 is a bottom perspective view thereof.

FIG. 6 is a top view thereof; and,

FIG. 7 is a back view thereof.

The broken lines shown in the drawings depict portions of the nasal spray device that form no part of the claimed design.
